CLAIM

The ornamental design for a recessed lighting fixture with independent adjustment between a light assembly and a driver assembly, as shown and described herein.

DESCRIPTION

FIG. 1 illustrates a view of the front side of a recessed lighting fixture.

FIG. 2 illustrates a cross-sectional view of the recessed lighting fixture.

FIG. 3 illustrates a perspective view of the recessed lighting fixture.

FIG. 4 illustrates a bottom-up view of the recessed lighting fixture; and,

FIG. 5 illustrates a perspective view of a top side of the recessed lighting fixture.

The broken lines in the drawings show portions of the recessed lighting fixture that form no part of the claimed design.

1 Claim, 5 Drawing Sheets
